EYE PROTECTION DEVICE

Charles H. Dockson and Harold S. Davis, Detroit,
Mich.

Application June 29, 1936, Serial No. 87,854

2 Claims. (Cl. 2-14)

The present invention relates to eye protection devices and particularly to eye protection goggles used for various purposes.

Prior to the present invention devices of this class have been formed of stampings or castings of aluminum or the like, or have been formed from castings of synthetic plastics, hard rubber, or other suitable materials. In all such cast devices the tensile strengths of the materials required thick sections to stand the strains imposed thereon. The goggles were, therefore, heavy and cumbersome and otherwise were objectionable to the wearer. In addition, the use of such castings in manufacturing devices of this class required that the shell of the goggles be constructed as solidly as possible and required that all openings therein be kept as small as possible. This resulted in impeded side vision opening and in inadequate ventilation inside the goggle.

In addition, these prior devices were not always satisfactory under certain conditions. For example, in the event of a direct blow being received on the face portion of the lens, cases are known where the rim or bezel was sprung from the eye cup and no clamping action was exerted on the outer edge of the lens, so that when the lens was shattered the glass therein was allowed to fly in various directions. Wherever large openings were provided in eye cups, the eye cups also were easily broken.

It is, therefore, an object of the present invention to provide an eye protection device which is light in weight and formed of materials having a relatively high tensile strength, and which has the maximum openings required to permit substantially unimpeded side vision and adequate ventilation of the goggles.

It is a further object of the present invention to provide an eye protection device which is easily adjusted to meet the requirements of a particular user and in which a positive clamping action is exerted at all times upon the edges of the lens, so that the particles of the lens are held firmly in place in the device even though the lens may be fractured.

Another object of the invention is to provide an eye protection device which is quickly and easily adjusted by the wearer.

Another object of the invention is to provide an eye protection device having an insulating cushion member interposed between the device and the face of the wearer.

The above and other objects and advantages of the invention will appear from the following description and appended claims when considered

in connection with the accompanying drawings forming a part of this specification.

Fig. 1 is a fragmentary elevation with parts broken away of an eye protection device embodying the present invention.

Fig. 2 is an elevation taken substantially on the line 2-2 of Fig. 1 in the direction of the arrows.

Fig. 3 is a side elevation taken substantially on the line 3-3 of Fig. 1 in the direction of the arrows.

Fig. 4 is a sectional view taken substantially on the line 4-4 of Fig. 1 in the direction of the arrows.

Fig. 5 is a fragmentary elevation taken substantially on the line 5-5 of Fig. 4 in the direction of the arrows.

Fig. 6 is an elevation of one lens of the device embodying the present invention, illustrating the effect of an impact which shatters the lens.

Fig. 7 is a side elevation of a modified form of a covering for the eye view openings.

Fig. 8 is a front elevation of a modified form of eye protection device embodying the present invention.

Fig. 9 is a side elevation with parts broken away of the eye protection device shown in Fig. 8.

Fig. 10 is an elevational view, partially in section, taken substantially on the line 10-10 of Fig. 8 in the direction of the arrows.

Fig. 11 is a sectional view taken substantially on the line 11-11 of Fig. 8 in the direction of the arrows.

Fig. 12 is a sectional view taken substantially on the line 12-12 of Fig. 9 in the direction of the arrows.

Fig. 13 is a fragmentary top elevation of an eye cup forming a part of an eye protection device embodying the present invention.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring to the drawings and particularly to Fig. 1, a device embodying the present invention comprises a pair of right and left eye cups 10 and 11, which are joined at the nose portion by an adjustable bridge member 12, which in the pres-

ent instance comprises a ball link chain section 13 and a flexible resilient covering 14 which extends over the central portion thereof.

Bezels 15 and 16 are screw threaded to the outer rims of the cups 10 and 11, as shown in Fig. 4. The screw threads here provided are relatively large threads so as to provide adequate strengths to withstand shocks and strains without stripping the threads. The device may be maintained on the head of the user by means of an adjustable head band 17 which is secured to the rear edges of the rim portions of the eye cups 10 and 11. A preferred method of attaching the head band 17 is shown in Fig. 4 and comprises a slot 20 (Fig. 4) which extends through the rim 21 of the eye cup. The strap 17 may be folded upon itself and fastened as at 22 so as to provide a thickened section which prevents its removal rearwardly through the slot 20. Any suitable adjusting means may be provided on the head band 17 so as to adjust the band for various head sizes. The band 17 may be formed of any suitable material such as elastic, webbing, or leather straps or other suitable materials.

25 A side opening 23 is provided in each of the eye cups to provide for side vision through the device and also to provide for ventilation inside of the eye cups. In the embodiment shown in Figs. 1-6 inclusive, the side opening 23 is closed by 30 a screen section 24, which may be of any suitable mesh or construction depending upon the use to which the device is to be put. The screen may be woven or punched of Monel metal, stainless steel or other material as desired. The screen section 35 24 is preferably formed as an integral part of the eye cup by casting the eye cup frame around the edges of the preformed screen insert. Additional strength can be imparted to the edge sections if desired, by extending the screen edges to the outer edges of the eye cup frame members. This permits the use of even smaller sections without sacrificing the desired strength in the construction. Also, Bakelite or other synthetic materials may be used when reinforced in this manner. 40 If desired, however, the screen section 24 may be held in a frame and the entire frame secured over the eye cup opening as by riveting, screws, clamping or other suitable method. As in the drawings, (Fig. 10), a ventilating opening may also be provided in the portion of the eye cup adjoining the bridge portion. Such openings will normally be covered with a screen member similar to the member 24 as previously described or a pre-formed screen member cast integrally therein.

55 Lenses 25 and 26 are provided and close the forward portion of the eye cups 10 and 11. The lenses are held in place by the bezels 15 and 16 and are clamped against a flat forward peripheral clamping edge 27 (Fig. 4). The lenses 25 and 26 60 may be formed of any desired type of transparent rigid material, such as glass, fused quartz, moulded plastics or the like.

The bridge member 12 of the device is made readily adjustable by means of openings 30 and 65 slots 31 (Fig. 5) provided in the eye cups 10 and 11. The openings 30 are of a sufficient size to permit the passage therethrough of the ball portions of the chain 13, whereas the ball portions cannot pass through the slot 31. After the desired 70 length of the bridge member 12 has been determined, the ball link chain 13 is cut so as to provide a single ball portion on the inside of the eye cup, as shown in Fig. 4. The eye cups are provided with recessed portions 32 so that but approximately one-half of the ball extends inside

of the eye cup, so that there is no impairment of vision thereby. The section of the eyecup 10 adjacent the slot 31 is of a thickness which is but slightly less than the distance between successive balls forming the ball chain 13 so that the chain 5 is held tightly in the seat. As here shown, the rims of the bezels 15 and 16 extend over the enlarged part of the slots and hold the ball chain securely in place.

In the modification shown in Figs. 8-13 inclusive, 10 the eye protection device consists of eye cups 50 and 51 having bezels 52 and 53 secured there-to.

In the embodiment here shown, the eye cups are joined by a bridge or bar member 56, which is formed of a bendable metallic substance such as brass, nickel, silver, or other suitable material, so that the distance between the eye cups may be adjusted by the user by bending the bridge or bar member 56. The bridge or bar member 56 may be 20 covered with a suitable flexible covering 66, if de-sired.

The eye protection device in this embodiment is maintained in place on the user by temples 57 and 25 58, which, as shown in Fig. 9, are pivotally se-cured to the eye cups as at 59 so as to permit a vertical swinging movement about a pivoting point 59. The temples also are pivoted as at 60 to provide for a horizontal pivotal movement about the point 60. In this manner the temples 30 are permitted to move pivotally either vertically or horizontally to accommodate various conditions encountered by various users. The temples are preferably formed of a flexible material which may be bent at the ear-engaging portion so as to 35 vary the effective length of the temples.

The eye protection devices as here shown may be provided with ventilating openings 61 and 62, 40 which openings may be covered by suitable fine mesh screen members 63 and 64, which are pre-formed and may be cast as an integral part of the eye cup members. The opening 61 is provided on the outside edge of the eye cups at a point ad-jacent the point of connection with the temples and the opening 62 is provided in the portion of 45 the eye cup adjacent the nose contacting portion. In this manner cross ventilation may be pro-vided in the interior of the eye cups which prevents steaming of the lenses and adds greatly to the comfort of the user of the devices.

The screen members 63 as shown in Fig. 12, 50 may be cast in the eye cup 51 in such a manner as to extend not only across the opening 61, but also to extend across the frame members forming the eye cup 51 and to act as a reenforcing member which 55 will greatly increase the resistance of the frame members to breakage. The screen members 64 are similarly cast in the frame members and not only cover the opening 62, but also extend through the frame surrounding the opening 62 and act in 60 a similar manner as a reenforcing member.

The bridge or bar member 56, as shown in Fig. 11, may comprise a central member 65 covered with a suitable resilient covering 66 which may be formed of rubber or other similar materials. 65 The bridge or bar member 56 is secured at its ends to the top portions of the eye cups, as shown in Fig. 11, so that it does not contact with the face of the user nor impair vision, the function of the member 56 being to act as a spacer bar to hold the 70 separate eye cups in a predetermined position.

The bezels as shown in the various views are provided with suitable raised portions 67 which are cast integrally therein and provide a ready 75

means for gripping the rim portions of the bezel for moving the bezel relative to the eye cups.

In certain uses of the eye protection device herein disclosed, it has been found that a metal section 5 of the eye cup will transmit heat to the face of the user in such a manner as to cause some discomfort. In addition, the use of such devices for a long period of time with the edges of the eye cups in tight contact with the face of the user 10 also causes discomfort. Accordingly, we have provided a face pad 70 (Figs. 12 and 13) which may be formed of rubber or other suitable cushioning material which is a substantial non-conductor of heat or electricity. The face pad 70 may 15 be used with any form of eye protection devices shown in the drawings and is so formed as to provide a straight wall portion 71 which is adapted to fit the inner side of the face surface of the eye cup and has a curved groove 72 to fit the contour 20 of the outer side of the rim of the eye cup to provide the necessary tension to retain the face pad in place thereon. A rib 73 is provided to give added tension to assist in holding the face pad in place. A relatively thick section 74 is provided at 25 the point of engagement of the face pad with the face of the user to provide the maximum cushioning effect of the device.

The face pad 70 may be formed of various types of materials, such for example as soft molded 30 rubber, sponge rubber, and the like, and the rubber may be either gum rubber or synthetic rubber, or the device may be formed of other types of resilient molded materials. The material selected should preferably be a non-conductor of both heat 35 and electricity and should be quickly and easily replaceable.

The face pad 70 may be replaced if the devices are to be used by different workers, and since this is the point of principal contact of the devices 40 with the faces of the users, the provision of the face pad 70 permits of easy cleaning. The face pad member 79 is provided with a suitable cast slot so that it may be placed upon the device or removed from the device by permitting either the 45 head band or the temple to slide through such slot.

A feature of great importance in a device embodying the present invention is that the side openings 23 or 61 in the eye cups 10 and 11 or 50 50 and 51 providing for side vision or for ventilation, may be of such sizes as to provide for maximum vision and ventilation. In a typical embodiment of the invention, the side openings 23 or 61 comprise in excess of approximately forty percent of 55 the total surface area of the half section of the eye cup in which the opening is provided and omitting the area of the thread section. This compares with a maximum opening area of approximately thirty to thirty-five percent of the same 60 surface in conventional types of construction. However, the increased opening area in devices of the present invention has approximated forty-five percent of such surface without substantial impairment of the strength of the eye cups, where- 65 as an eye cup of conventional cast construction having openings of approximately thirty to thirty-five percent of the surface area is substantially impaired in strength and consequently is subjected to excessive breakage.

70 The foregoing unique features of construction may be achieved as in the present instance by the formation of the eye cups 10 and 11 or 50 and 51 and of the bezels 15 and 16 or 52 and 53 from die castings, such for example as those formed of light 75 metal alloys. In one preferred embodiment such

alloy may contain approximately ninety-two percent magnesium and eight percent of aluminum. Such an alloy has a tensile strength of approximately 22,000 pounds per square inch with an elongation of approximately four percent. This 5 tensile strength of the alloy permits its use to provide the framework of the eye cups 10 and 11 or 50 and 51. By actual test, it has been found that the eye cups will stand approximately 150 pounds of dead weight on the side frames having in excess of approximately forty percent of side surface area in the side openings 23 or 61 without fracturing of the frame. It is this extreme strength which permits the use of such thin cross sections and the provision of such large openings for ventilation and side view through the devices. 10 15

Also, the use of this type of construction permits the formation of very accurate screw threads 35 at the point of engagement between the bezels 15 and 16 or 52 and 53 and the eye cups 10 and 20 11 or 50 and 51. The strength of the screw-threaded portion is such that a blow of sufficient force to fracture the lenses 25 and 26 will not cause a springing of the bezel or a stripping action on the screw threads 35 with a consequent loosening of the clamp between the bezel and the forward edge of the eye cups on the peripheral edge 25 of the lens.

A condition where a force has been exerted sufficient to fracture the lens is shown in Fig. 6, 30 and this view illustrates accurately the fact that in using a lens of case-hardened glass or the like construction, the entire lens is clamped securely in place in the device even though it may be broken into separate fragments. This is due to 35 the construction herein provided in which the tensile strength of the screw-threaded portion is greater than the forces required to break the lenses. This result also may be achieved by using bezels of high tensile strength and wide screw-threaded sections on eye cups formed of suitable 40 materials reenforced with the reenforcing screens as previously described.

The alloy above mentioned is a very light alloy and the entire device here shown is sufficiently 45 light so that when combined with the ventilation, side vision and accurate contour design of the present structure it affords maximum comfort to the user.

In finishing the devices herein disclosed, it is 50 essential that the finish should pass the standard salt and corrosion tests for metal devices of this character. A suitable finish of this type has been provided by the use of synthetic baking enamels or similar materials with which the finished metal 55 parts are sprayed and then subjected to baking at elevated temperatures. The finish thus provided is a high gloss finish which is flexible as well as resistant to both salt and corrosion and prevents excessive deterioration of the metal 60 parts.

In the modified form shown in Fig. 7, an insert 40 is provided to enclose the openings 23 or any other openings which may be provided in the eye cup walls in the event that the device is to be 65 used under circumstances where an air-tight opening is desired which will permit the maximum side vision. The member 40 is provided with a frame 41 which is shaped to fit tightly into the openings 23 and the frame is covered 70 with a window 42 of transparent material, such as cellulose acetate, or other suitable material. If desired, this member may also be cast integrally in the eye cups as previously described in connection with the screen insert. 75

If desired, the foregoing described constructions may be modified by providing a single screen member in the general shape of the eye cups and then casting the materials used in forming the 5 eye cups, around and through the openings in the screen member. In this way the entire body portion of the eye cup structures would be reinforced by the screen member and the one screen member would extend over all openings provided 10 in the body portion.

We claim:

1. In an eye protecting device, an eye cup adapted to hold a lens, said cup being made of a light weight metallic alloy, a reinforcing and 15 comfort rib around the edges of said cup at one of its ends adapted to fit against the face of the bearer and formed integrally with said cup, said cup being provided with a ventilation side opening, and a ventilation and reinforcing screen 20 covering said opening and cast into the material

of the cup for a substantial distance beyond the edges of said cup at said opening for reinforcing said edges.

2. In an eye protecting device, an eye cup adapted to hold a lens at one of its ends, said cup being made of a light weight metallic alloy 5 containing a substantial amount of magnesium, a reinforcing and comfort rib of substantially round cross section provided on the opposite end of said cup and formed integrally therewith, said cup 10 being provided with a ventilation side opening, the area of said opening being at least forty percent of the total area of one side surface of said cup, and a ventilation and reinforcing screen 15 covering said opening and cast into the material of the cup for a substantial distance beyond the edges of said cup at said opening for reinforcing said edges.

CHARLES H. DOCKSON.
